UNITED STATES PATENT OFFICE.

ERNEST W. FREEMAN, OF BELLEVILLE, NEW JERSEY, ASSIGNOR, BY MESNE ASSIGNMENTS, TO CONTINENTAL CAN COMPANY, INC., OF NEW YORK, N. Y., A CORPORATION OF NEW YORK.

CONTAINER.

Application filed August 24, 1927. Serial No. 215,033.

My invention relates to improvements in containers of the slip cover variety which are provided with external beads or projections between which an implement, such as 5 a coin, knife or the like, may be inserted for prying the cover loose.

An object of my invention is to provide the body member and the cover member of the container with opposing outwardly projecting beads or projections, the bead on one 10 of the members, such as the body, having one or more portions substantially on the same plane through the body and an intermediate portion offset from said plane to admit an 15 implement between opposing beads, and on opposite sides of said intermediate portion the corresponding bead is inclined gradually toward the first named portions so that the space between the opposing beads gradually 20 decreases from the intermediate portion of the first named bead, whereby a tool inserted in the wider space between the beads may be rotated to pry the cover from the body, and may be pushed or rolled between 25 the beads so as gradually to advance through the decreasing space between the beads to serve in a wedge-like manner to loosen the cover on the body, whereby the cover may be readily removed.

30 My invention comprises novel details of improvement that will be more fully hereinafter set forth and then pointed out in the claim.

Reference is to be had to the accompanying drawings forming a part hereof, wherein

Fig. 1 is a side view of a container or box embodying my invention;

Fig. 2 is a vertical section of Fig. 1;

40 Fig. 3 is a perspective view of the body, and

Fig. 4 is a side view illustrating the position of a coin during the prying of the cover loose from the body of the container.

45 Similar numerals of reference indicate corresponding parts in the several views.

My improved container comprises a body member 1 and a cover member 2, which may be of any well known construction, such as 50 commonly called tin cans, wherein the body and the cover may, if desired, be stamped each from a single piece of metal. The body 1 is provided with an external bead 3 which may be formed by forcing a portion of the 55 metal of the side wall of the body outward-

ly in the form of a projection and preferably squeezing the same together, as illustrated in Fig. 2, providing a portion 1^a of the body at the open end beyond the bead to receive the skirt 2^a of the cover with a 60 substantially tight fit, as illustrated in Fig. 2. The edge of the body may be straight, as shown, or curled in a well known way. The bead or projection 3 has several portions 3^a located substantially on a plane through 65 the body, said portions thereby being level, there being preferably three of such portions located around the body in equal spaced relation, and at an intermediate point 3^b between each two portions 3^a the bead 3 is offset from said plane a suitable distance. The upper surface of the bead 3 on opposite sides of a portion 3^b inclines toward the adjacent higher portion 3^a in a gradually slanting direction. The skirt 2^a of the cover is provided at its edge with an outwardly extending bead or projection 2^b which is shown on the same plane throughout at the edge of the skirt, which bead may be formed by rolling 70 the edge of the skirt.

When the cover is upon the body the bead 2^b is adapted to rest against the higher portions 3^a of the bead 3 of the body, as illustrated in Fig. 1, to properly position the cover upon the body and whereby recesses 85 at 3^c are provided between the beads 3 and 2^b in which an implement, such as a coin 4, or other suitable tool, may be inserted for prying off the cover. When the coin or the like is in the wider portion of a recess 3^c the 90 coin may be rotated or twisted so as to bear against the opposing beads to pry the cover loose. However, (particularly should the cover adhere to the body tightly), the coin or tool may be rolled or pushed around the body 95 between the beads, whereby by reason of the gradual inclination of the bead 3 from its low point 3^b to a high point 3^a, as viewed in Fig. 1, the coin or tool will be gradually forced in a wedge-like manner between the two beads to cause initial release of the cover 100 from the body, and at any convenient point of the coin along the container the coin may be turned or twisted for finally prying off the cover.

I am aware that containers having spaced beads are known, between which beads a coin or tool may be placed for prying the cover from a container body, but in such containers the construction is such that turning 110

or twisting only of the coin or tool is provided for so that when the cover adheres to the container body very tightly it is quite difficult to cause release of the cover from the body. In accordance with my invention the coin or tool may be rolled or pushed into the gradually decreasing space between the two beads on either side of the wider recess so that the wedging action of the coin or tool between the beads performs the novel effect of starting the release of the cover from the body.

Having now described my invention what I claim is:—

15. A metal container comprising a body member provided with an external projecting bead formed in the side wall thereof at a distance beneath the upper edge of the container, a cover member for said body provided with a projecting bead at its extreme lower edge lying in a plane parallel with the plane of the top portion of the cover mem-
- 20.

ber whereby when said cover member is placed on said body member the beaded edge portion of the cover member will have a uniform friction grip upon the portion of the body member above its bead throughout the entire circumference thereof for holding the cover on the body member, said bead on the body member having three or more portions spaced substantially at an equal distance from each other and lying in a plane parallel with the upper edge of the body member for providing stops to limit the movement of the cover member onto the body member, the portions of the bead between said stops being gradually inclined away from the edge of the body member whereby an instrument placed between the inclined portion of the bead on the body member and the bead at the lower edge of the cover may be used for wedging or prying the cover member loose from the body member.

ERNEST W. FREEMAN.
